CARRIER FOR BRAIDING MACHINES

Anker Petersen, Boston, Mass., assignor to James Joseph Lannon, West Newton, Mass.

Application September 21, 1937, Serial No. 164,891

18 Claims. (Cl. 96—13)

This invention pertains to braiding machines, especially machines of the general type disclosed in the patent to Petersen No. 1,796,938, dated March 17, 1930, and relates more particularly to bobbin carriers for use in such machines.

In my copending application for Letters Patent Serial No. 107,206, filed October 23, 1936, I have disclosed an improved braiding machine useful, for example, in interbraiding flat ribbon-like strands, for instance, flat metal ribbons, so as to form a tubular braid appropriate, among other things, to constitute a conduit for electrical conductors. While such flat strands of metal are useful for the purpose and can be successfully and expeditiously interbraided by the machine disclosed in the aforesaid application, I find that under certain conditions it is preferable to form each flat strand by disposing a plurality of small independent filaments, such, for example, as metal wires, in parallel relation and in substantially the same plane, rather than to use an integral metal ribbon, and the principal object of the present invention is to provide a carrier operative to support a series of spools or bobbins each carrying a supply of fine wire or the like and with provision for properly tensioning the wires from the several bobbins and for delivering the several wires in substantially parallel relation in readiness for assembly to form a flat strand.

A further object is to provide a carrier comprising simple and effective feeler or detector means cooperable with each individual bobbin of the carrier and operative in response to substantial or complete exhaustion of the wire mass on any bobbin to initiate operation of a stop motion. A further object of the invention is to provide a simple means for receiving and supporting the several bobbins in the carrier in such a way as to permit removal of any individual bobbin and its replacement without disturbing the other bobbins in the carrier.

Other objects and advantages of the invention will be made manifest in the following more detailed description and by reference to the accompanying drawings, wherein

Fig. 1 is a plan view, with certain parts broken away, illustrating a bobbin carrier embodying the present invention;

Fig. 2 is an elevation of the carrier of Fig. 1 viewed from the left-hand side of the latter figure;

Fig. 3 is a fragmentary section, to larger scale, substantially on the line 3—3 of Fig. 1;

Fig. 4 is a view similar to Fig. 1 but illustrating a carrier of another type;

Fig. 5 is an end elevation of the carrier of Fig. 4, viewed from the left-hand side of said figure, and partially in vertical section substantially on the line 5—5 of Fig. 4; and

Fig. 6 is a fragmentary diagrammatic plan view, to smaller scale, illustrating a braiding machine of the type to which the present invention relates and showing the relative position of the inner and outer sets of bobbin carriers, and the location of stop mechanism parts.

Referring to the drawings, the numeral 1 designates a bobbin carrier embodying certain features of the present invention, such carrier being designed to constitute one of the inner set of carriers of a braiding machine of the type above referred to. This carrier comprises a rigid frame 2 having a guide roll 3 at its inner end designed to run in a circular track or guideway 4 (Fig. 6) forming an element of the braiding machine. The carrier is also furnished with guide rolls 5 at its outer end designed to engage a groove or guideway in the inner surface of the ring 6 (Fig. 6) forming an element of the braiding machine. Preferably the rolls 3 and 5 are mounted on anti-friction bearings and are of self-lubricating type, as described for example in the patent to Petersen, No. 1,796,938, dated March 17, 1931.

In accordance with the present invention, a fixed shaft 7 (Fig. 1) is arranged to extend transversely across the frame 2 from one side to the other and on this shaft there is mounted a series of bobbin supports 8. These bobbin supports are preferably blade-like members each pivoted at one end upon the shaft 7, the several supports 8 being held in properly spaced relation by means of sleeves 9 mounted on the shaft 7 between adjacent supports. Each of the supports 8 is furnished with a bobbin-receiving stud 9a, the several studs being axially aligned and fixed to the supports intermediate the ends of the latter, preferably being arranged so that each stud projects laterally from the corresponding side of its support. Each stud is of such diameter as to receive one of the bobbins or spools 10 on which the wire or other strand-forming material is wound.

In order to maintain the supports 8 in parallel relation, (it being noted that these supports are quite narrow in a horizontal direction so as to save space) the free ends of the several supports are designed to be received in slots or sockets formed in a substantially vertical plate 11 provided with a horizontal flange 12 (Fig. 3) by means of which it is secured to the carrier frame. 55

The slots in the plate 11 are of a width such as snugly to receive the free ends of the blade-like supports 8, such slots forming in effect sockets into which the ends of the supports may be swung 5 downwardly and thus held in operative position. In order to prevent accidental escape of the ends of the supports from their sockets, spring clips or latches 13 are arranged along the outer side of the plate 11, said spring clips or latches being held 10 in proper position by means of a clamping plate 14. Each of the supports 8 is preferably furnished with a notch 15 (Fig. 3) at its free end, and this notch is designed to receive the corresponding spring clip or latch 13 so as to hold the support in 15 normal operative position. However, the spring latch may readily be disengaged manually when it is desired to swing a given support upwardly about the axis of shaft 7, thereby to raise its stud 9^a up to a position in which the bobbin may be 20 placed on or removed from the stud.

In order to tension the strand-forming wires from the several bobbins, the carrier is provided with a rotary shaft 16 substantially parallel to the shaft 7, and this shaft 16 is furnished with a 25 ratchet wheel 17 at the outer side of the frame, and a pawl 18 is engageable with the ratchet wheel for holding the shaft 16 in any desired position of rotational adjustment. Fixed to the shaft 16 is a series of resilient tension fingers 19 30 (Fig. 2). Each of these fingers preferably consists of a length of flat spring wire doubled at its mid-point in its own plane so as to form a smoothly curved end 19b (Fig. 1) and to provide two substantially parallel runs of the flat resilient 35 material. The free end of each of these two runs is coiled to form a spring in the nature of a clock spring, and the inner end of each spring coil is fixed to the shaft 16. The free ends of the tension members 19 are arranged to underly the several 40 bobbins and the tension applied may be varied and predetermined by turning the shaft 16 and then holding it in adjusted position by means of the ratchet 17 and pawl 18.

When tensioning slippery material like fine 45 wire, paper, yarn, or the like, it is quite desirable to provide the tension fingers with some non-metallic substance to bear against the material on the bobbin in order to furnish a more uniform and reliable tension. For this purpose it has 50 been found that braided textile material threaded over the flat ribbon-like element forming the tension arm 19 affords the desired tensioning action and results in a uniform delivery of the strand-forming material. Thus, for example, before the flat metal ribbon forming the tension finger is doubled, a length of tubular textile braid 55 may be threaded over the metal ribbon, after which the metal may be bent as above described, thus providing the tensioning finger with the desired contact surface. On the other hand, if 60 desired the textile material or its equivalent may be slipped onto the tension finger after the latter has been completed and secured to the shaft 16. While braided textile fiber has been suggested as a desirable material, it is contemplated 65 that many other substances may be useful for the purpose, such, for example, as woven or felted textile fibers, cork, rubber, artificial rubber, leather or, in fact, any material of a yielding 70 character such as to distribute the contact over a substantial area of the material wound on the spool.

In the braiding machine disclosed in the co-pending application for Letters Patent above referred to, there is provided a stop mechanism 75

which operates automatically in response to the exhaustion of strand from any of the bobbins of either the inner or outer series. This stop motion includes a downwardly directed finger F' (Fig. 6) which, when swung out of its normal vertical position, breaks an electrical circuit and thereby causes the machine to stop. Since the stop mechanism itself is fully described in the aforesaid application, it is unnecessary to describe it further in detail here, but in accordance with the present invention the carriers are furnished with devices for actuating the finger F' upon exhaustion of the strand from any spool of any carrier.

For this purpose, as illustrated in Figs. 1, 2 and 3, the carrier is provided near its outer end with a transverse support or shaft 21 suitably fixed in position and provided with a series of forwardly and upwardly projecting brackets 22 (Fig. 3) corresponding in number to the several bobbin supports 8. Each of these brackets 22 is furnished 20 with a pivot stud 23 upon which is mounted a feeler or detector lever 24, one end of which is designed to rest upon the strand-forming material on the bobbin, while the other end 25 is designed at times to be so positioned as to engage 25 and actuate a finger F carried by a shaft, mounted to turn in the ring 6 and having a finger F² (Fig. 6) which may be positioned to engage the stop mechanism finger F'. Each detector finger 24 is provided with a spring 26, preferably of the 30 clock-spring type, designed to press the free end of the lever into contact with the strand-forming material on the corresponding bobbin. So long as the free end of the detector 24 is supported by strand-forming material, it occupies substantially 35 the position shown in full lines in Fig. 3, but upon exhaustion of the strand-forming material the spring 26 is enabled to swing the detector to the broken line position of Fig. 3 in which its end 25 is directed vertically up and is thus positioned 40 to engage the finger F during the revolution of the carrier and thus to cause the stop motion to act and stop the machine.

When the machine is stopped, the operator disengages the spring clip 13 from the bobbin support 8 upon which the exhausted bobbin is mounted and swings the support up about the shaft 7 so as to clear its stud 9^a from the other supports, thus permitting the operator to remove the empty bobbin from the stud and to replace it 45 with a filled bobbin. The operator then swings the detector finger 24 back to its normal position, —drops the end of the bobbin support back 50 into its slot in the plate 11, and engages the spring clip 13 with the notch 15, thus placing the 55 bobbin in operative position. The strand from the bobbin may now be led through the proper guides to the braiding point and the machine may again be started.

Referring to Figs. 4, 5 and 6, the numeral 1^a 60 designates a carrier of the outer series, such carrier comprising the frame 29 which is open at top and bottom and which supports the fixed transverse shaft 30 (Fig. 5) on which is mounted a series of blade-like bobbin supports 31. The free ends of these bobbin supports are received 65 in narrow vertical slots or sockets in the upper edge of the inner wall 29^a of the carrier frame, and these free ends of the supports are normally held in the slots by means of the spring 70 clips 32 fixed to the wall 29^a and which are releasably received in notches 33 at the free ends of the supports 31. Each support 31 is furnished with a bobbin receiving stud 31^a (Fig. 4) and the several supports are spaced apart by means 75

of collars 32 on the shaft 30 and intervening guide pulleys 32^a also mounted on the shaft 30. Each guide pulley 32^a is so disposed as to receive the strand from a spool mounted on the corresponding stud 31^a and to deliver such strand at a point outside of the outer wall of the carrier frame.

Below the shaft 30 there is mounted a rotatable tension supporting shaft or rod 34 (Fig. 5) to which are fixed the inner ends of clock spring coils constituting integral parts of resilient tension fingers 35 similar to the tension fingers 19 above described. Each of the tension fingers 35 may be provided with resilient yieldable contact material 36 such as described in connection with the tension fingers of carrier 1.

Near the forward end of the carrier there is arranged a fixed transverse shaft 36^a provided with a series of upstanding brackets 37 corresponding in number to the number of bobbins and each forming a support for a lateral stud 38 on which is mounted a feeler or detector finger 39. A coil spring 40 tends to swing the free end of each detector finger to the left as viewed in Fig. 5 so as to contact with the strand-forming material on the corresponding bobbin.

About midway between the inner and outer ends of the frame of the carrier there is mounted a rock shaft 41 (Fig. 5) provided near its opposite ends, at points just inside the frame, with arms 42 which support a contact rod 43 extending transversely across the carrier. The rock shaft 41 is also provided with a lever arm 44 which is engaged by a light spring 45 which tends to hold the arm 44 in full line position of Fig. 5 so that the arms 42 extend upwardly and occupy the full line position shown in Fig. 4.

Mounted on studs projecting from the outer surface of the outer wall of the frame 29 is a series of guide rolls or pulleys 46 (Fig. 5). Each of these guide rolls or pulleys preferably is grooved and is designed to receive one of the wires from one of the bobbins after the wire leaves the corresponding guide pulley 32^a. The pulleys 32^a and 46 are so arranged that a wire, after leaving the spool, is guided to the outer side of the frame and then downwardly in parallel relation to the outer surface of the frame of the carrier, and from the several pulleys 46 the wires are designed to extend in substantially parallel relation to a guide pulley (such as the pulley 86 of my aforementioned copending application) carried by the ring 6 of the braiding machine.

If a strand-forming wire carried by one of the bobbins of the carrier 1^a is exhausted, the feeler finger 39 drops and in so dropping engages the contact rod 43, thus swinging the arms 42 downwardly and raising the arm 44 into the path of the finger F' so that as the carrier revolves the finger F' is actuated and thus the machine is stopped. When the machine has been stopped, the bobbin support 31 may be disengaged from the spring clip 32 and raised so as to clear its stud 31^a, with the bobbin thereon, from the adjacent supports 31, thus enabling the operator to remove the empty bobbin and replace it with a filled bobbin. The free end of the carrier 31 may then be dropped down into its slot in the wall 29 of the carrier and reengaged with its spring clip 32. The wire from the bobbin is then let over the corresponding pulleys 32^a and 46 and about pulleys on the corresponding guide lever (not shown) and thence to the braiding point.

It is thus manifest that in accordance with the present invention both the carriers of the inner and outer sets are adapted to receive a substantial number of bobbins, all alike and all in coaxial relationship and all so supported that they may readily be removed individually for replenishment. It is further manifest that the carriers of both the inner and outer sets are furnished with effective tensioning means for each bobbin and that the several carriers are furnished with stop motion actuating devices corresponding to each individual bobbin and all effective to initiate the operation of the stop motion mechanism of the machine.

While a certain desirable embodiment of the invention has been illustrated and described by way of example, it is to be understood that the invention is not necessarily limited to this precise embodiment but is to be regarded as broadly inclusive of any and all equivalent arrangements which may fall within the scope of the appended claims.

I claim:

1. A bobbin carrier for braiding machines comprising a frame open at its top, and means for supporting a series of bobbins in coaxial relation in the frame, the supporting means comprising parts individually movable upwardly out of the frame and so designed and arranged as to permit any selected bobbin to be removed without disturbing the others.

2. A bobbin carrier for braiding machines comprising a frame and a series of bobbin supports each having a bobbin-receiving element, each bobbin support being movable independently of the others away from normal operative position so as to expose its bobbin-receiving element for the reception or removal of a bobbin.

3. A bobbin carrier for braiding machines comprising a frame, a plurality of bobbin supports carried by the frame, each support being independently movable to and from operative position, and releasable means normally retaining each support in operative position.

4. A bobbin carrier for braiding machines comprising a frame, a plurality of bobbin supports each pivotally mounted in the frame and movable from a bobbin-receiving position to a normal operative position, and releasable latch means normally holding each support in the operative position.

5. A bobbin carrier for braiding machines comprising a frame, a plurality of substantially parallel bobbin-supporting arms each pivotally mounted in the frame, a bobbin-receiving stud projecting laterally from each arm, the several arms being individually movable from a normal operative position to a bobbin-receiving position, and releasable means for holding each arm in normal operative position.

6. A bobbin carrier for braiding machines comprising a frame, a plurality of substantially parallel blade-like bobbin-supporting arms, each pivotally mounted adjacent to one of its ends so as to swing about a common axis, a bobbin-receiving stud projecting from one side of each arm intermediate the ends of the latter, means providing a socket for the free end of each arm when in operative position, and releasable means for retaining each such end in its socket.

7. A bobbin carrier for braiding machines comprising a frame, a plurality of substantially parallel bobbin-supporting arms, each pivotally mounted adjacent to one end to swing about a common axis, each arm having a bobbin-receiving stud

- and each arm having a recess adjacent to its free end, and a spring latch engageable with the recess thereby releasably to hold the arm in operative position.
5. 8. A bobbin carrier for braiding machines comprising a frame, a plurality of substantially parallel blade-like bobbin-supporting arms, each pivotally mounted adjacent to one end to swing about a common axis, a support extending transversely of said arms and having sockets for the reception of the free end of each arm, and a bobbin-receiving stud projecting from one side of each arm, the several studs being coaxial and projecting from corresponding faces of the several arms.
10. 9. A bobbin carrier for braiding machines comprising a frame, means for supporting a series of bobbins in coaxial relation therein, and tension means for each of the bobbins so supported, said tension means comprising a rotatable shaft extending substantially parallel to the axes of the bobbins but spaced from the latter, a series of resilient tension arms each secured at one end to the shaft, each such arm having a free end 15 portion designed to engage the material upon one of the respective bobbins, and adjusting means for holding the shaft in predetermined position thereby to permit the tension to be varied.
15. 10. A bobbin carrier for braiding machines comprising a frame, means for supporting a series of bobbins in coaxial relation therein, and tension means for each of the bobbins so supported, said tension means comprising a rotatable shaft extending substantially parallel to the axis of the bobbins but spaced from the latter, a series of resilient tension arms each secured at one end to the shaft, and pawl and ratchet means for adjustably holding the shaft in predetermined position thereby to permit the tension to be adjusted.
20. 11. A bobbin carrier for braiding machines comprising a frame, means for supporting a series of bobbins in coaxial relation therein, and tension means for each of the bobbins so supported, said tension means comprising a rotatable shaft extending substantially parallel to the axes of the bobbins but spaced from the latter, a series of tension arms each secured at one end to the shaft, each said arm comprising a length of resilient metal doubled to provide two adjacent substantially parallel portions integrally joined at the free end of the arm, the opposite end of each of said parallel portions being coiled like a clock spring, the inner end of each coil being fixed to the shaft.
25. 12. A bobbin carrier for braiding machines comprising a frame, means for supporting a series of bobbins in coaxial relation therein, and tension means for each of the bobbins so supported, said tension means comprising a rotatable shaft extending substantially parallel to the axis of the bobbins but spaced from the latter, a series of resilient tension arms each secured at one end to the shaft, each such arm comprising a length of resilient metal, and a sleeve of yieldable material telescoped over the metal forming the arm.
30. 13. A braiding carrier for use in a braiding machine equipped with a stop-motion mechanism, said carrier comprising a frame and means operative to support a series of bobbins in the frame in coaxial relation, and a strand exhaustion detector for each individual bobbin, each detector comprising a pivotally supported arm arranged to have its free extremity normally in contact with the material upon its respective bobbin, sup-
- porting means defining an axis parallel to the axes of the bobbins about which said detector may swing, and a spring normally urging said detector toward the material upon its respective bobbin.
35. 14. A braiding carrier for use in a braiding machine equipped with a stop-motion mechanism, said carrier comprising a frame and means operative to support a series of bobbins in the frame in coaxial relation, and a strand exhaustion detector for each individual bobbin, the said detectors being so constructed and arranged that each will individually actuate the stop mechanism upon exhaustion of strand material from its corresponding bobbin.
40. 15. A braiding carrier for use in a braiding machine equipped with a stop-motion mechanism, said carrier comprising a frame and means operative to support a series of bobbins in the frame in coaxial relation, and a stop-motion actuating arm mounted on the carrier, a series of coaxial detector levers mounted on the carrier, one for each bobbin, and an arm-actuating part engageable by any individual detector lever upon exhaustion of the material from its respective bobbin thereby to move said arm into stopping position.
45. 16. A braiding carrier for use in a braiding machine equipped with a stop-motion mechanism, said carrier comprising a frame and means operative to support a series of bobbins in the frame in coaxial relation, a rock shaft mounted in the carrier substantially parallel to the axes of the bobbins, a stop-motion actuating arm fixed to said shaft, spring means normally holding said arm in inactive position, a pair of parallel arms secured to the rock shaft adjacent to opposite ends respectively of the carrier, a contact bar supported by said parallel arms, and a series of detector fingers mounted to swing about an axis substantially parallel to that of the bobbins, each detector finger normally contacting material upon a corresponding bobbin, each finger, when freed by exhaustion of said material, moving into engagement with said contact bar and thereby moving the actuating arm into operative position.
50. 17. A bobbin carrier for braiding machines comprising a frame having inner and outer walls, and means for supporting a series of bobbins in coaxial relation in the frame, and a series of strand guide pulleys each corresponding to one of the bobbins arranged adjacent to the outer wall of the frame, each pulley being so designed as to receive a strand leading from the corresponding bobbin and to guide said strand over the edge of said outer wall.
55. 18. A bobbin carrier for braiding machines comprising a frame having inner and outer walls, and means for supporting a series of bobbins in coaxial relation in the frame and a series of strand guide pulleys each corresponding to one of the bobbins arranged adjacent to the outer wall of the frame, each pulley being so designed as to receive a strand leading from the corresponding bobbin and to guide said strand over the edge of said outer wall, and a second series of guide pulleys disposed at the outer side of said wall, said latter pulleys turning in substantially the same plane and being arranged to receive strands from the several pulleys of the first set and to deliver the strands in paths substantially parallel to the outer surface of the outer wall of the carrier.
